Assistant Examiner — Sydney Margaret Parsley

(74) Attorney, Agent, or Firm — Bennett David, Esq.

(57) **CLAIM**

The ornamental design for an underwater living space for recreational diving, as shown and described.

DESCRIPTION

FIG. 1 depicts a perspective view of an underwater living space for recreational diving;

FIG. 2 depicts a side view thereof;

FIG. 3 depicts a side view thereof;

FIG. 4 depicts a rear view thereof;

FIG. 5 depicts a front view thereof;

FIG. 6 depicts a top view thereof; and,

FIG. 7 depicts a bottom view thereof.

The broken lines are for the purpose of illustrating portions of the underwater living space for recreational diving that form no part of the claimed design.

1 Claim, 7 Drawing Sheets
